CHILD'S GARMENT

Joan M. Brennan, St. Paul, Minn., assignor to
 Munsingwear, Inc., Minneapolis, Minn., a cor-
 poration of Delaware

Application June 17, 1946, Serial No. 677,172

4 Claims. (Cl. 2—80)

1

This invention relates to a garment, and while the invention might have other applications, it particularly is designed to be applied to a child's garment. It is desirable that the young child or baby have a garment that simplifies diaper changing; and, for the sake of appearance, a garment that covers the diaper completely.

It is a further object of the invention to provide a garment having a portion extending above the waist and providing arm and neck openings, together with a portion extending downwardly at the front of the garment and having a free end, said latter portion being adapted to be passed rearwardly between the legs and then folded upwardly to said first mentioned portion and then to have its corner portion extending around to the front of the garment together with appropriate fastening means for folding said second portion in such position.

It is another object of this invention to provide such a garment as set forth above, in which a minimum of button fastenings on the outer garment allows easy access to the diaper on the child. A simple manipulation of the lower part of the garment conveniently permits a diaper change without removing the upper portion of the garment. A waterproof layer is attached to the lower area of the garment and eliminates the separate operation of putting on rubber pants to keep the outer garment dry. Because the lower area of the garment follows the outline of a kite-fold diaper which will be worn underneath, the diaper is completely concealed by the outer wrapping of the garment.

It is also an object of the invention to provide such a garment as set forth in the preceding paragraph, together with a layer of waterproof material detachably secured to the inner side of and substantially covering said second portion.

It is still another object of the invention to provide a child's garment having a portion extending above the waist at the front and rear thereof and providing neck and sleeve openings, a second portion extending downwardly at the front of said first portion, the sides thereof diverging to a free end of the same, which end is substantially horizontal, fastening means adjacent the ends of said free end and intermediate the ends thereof, said first mentioned portion having fastening means adjacent the waistline at the front and rear thereof, said second portion being adapted to be folded upwardly and have the fastening means intermediate the ends of its free ends secured to the fastening means at the rear of said first mentioned portion and being adapted to have its corner portions passed around to the front of the garment and the fastening means adjacent the ends of its free ends secured to the fastening means at the front of

2

said first mentioned portion, thus providing leg openings.

It is also an object of the invention to provide such a garment as set forth in the preceding paragraph, said second portion having spaced fastening means at its top and bottom at its inner side, and a layer of waterproof material having spaced fastening means adjacent its top and bottom adapted to cooperate with the fastening means on said second portion to secure the same thereto.

It is another object of the invention to provide such a garment as set forth in the preceding paragraph save one, said second portion preferably having a belt secured along its free end and being preferably stretchable longitudinally along said end, together with means connected to said first mentioned portion adapted to have a diaper secured thereto.

These and other objects and advantages of the invention will be fully set forth in the following description made in connection with the accompanying drawings in which like references characters refer to similar parts throughout the several views and in which:

Fig. 1 is a view in front elevation of the garment in extended position;

Fig. 2 is a view in rear elevation;

Fig. 3 is a view in rear elevation with the garment in operative position;

Fig. 4 is a view in front elevation with the garment in operative position;

Fig. 5 is a vertical section taken substantially on line 5—5 of Fig. 2, the rear of the garment being omitted;

Fig. 6 is a view in front elevation of a modified form of garment showing the same in extended position;

Fig. 7 is a view in rear elevation of the garment shown in Fig. 6 in extended position;

Fig. 8 is a view in rear elevation of the same in operative position; and

Fig. 9 is a view in front elevation with the garment in operative position.

Referring to the drawings, a garment 10 is shown having a portion 10a which extends above the waist at the front and rear and over the shoulders, the same providing a neck opening 10b. Portion 10a also provides sleeve openings 10c and sleeves may be secured about said openings which may be of any desired length, but which in the embodiment of the invention illustrated are shown as quite short bands 10c. While portion 10a could be opened at front or back in the embodiment of the invention illustrated it is shown as closed and adapted to be put on over the head of the wearer. A band 10d extends about neck opening 10b and this as well as the sleeve portions 10c may be somewhat elastic or stretchable circumferentially. Portion 10a has

secured thereto adjacent the waistline and substantially centrally of its front, a fastening means 11. While this could take various forms, in the embodiment of the invention illustrated it is shown as a button. Said portion 10a at its rear also has another fastening means 12 disposed substantially centrally of its rear side, and while this could take various forms, it also is illustrated as a button. A portion 10e extends downwardly from the front side of portion 10a and it may be continuous of portion 10a or formed of a separate piece connected along the line 10f by a suitable seam. Portion 10e extends downwardly and the sides thereof extend downwardly and outwardly so that the same flares toward a free end, which end extends substantially horizontally or transversely of the garment. Said free end of portion 10e is preferably provided with a strip or belt 10g. Belt 10g or a portion 10h thereof intermediate its end is preferably made of elastic material so that said belt can stretch longitudinally. Portion 10e also has its edge portion 10p adjacent belt 10g made stretchable or elastic. While this could be done in various ways, in the illustrated embodiment an elastic cord is inserted along said edge portion, which edge portion is somewhat gathered, as shown in Figs. 1, 2 and 4. Portion 10e is provided with fastening means 10i adjacent its free corners which are adjacent the ends of belt 10g, which fastening means are illustrated as buttonholes. Said free end of portion 10e is also provided with fastening means intermediate its ends, one of which 10j is illustrated as a buttonhole disposed substantially centrally of said free end or belt 10g. Portion 10e at its inner side, shown in Fig. 2, has spaced fastening means 10k adjacent its upper end and has spaced fastening means 10m adjacent its lower end. While said fastening means might take various forms, in the embodiment of the invention illustrated they are shown as small tabs having buttonholes therein. A layer of waterproof material 13 is provided having a shape similar to portion 10e and the same has thereon spaced fastening means 14 adjacent its upper end and spaced fastening means 15 adjacent its lower end. While the type of fastening means 14 and 15 could be varied, they are shown as buttons adapted to cooperate with fastening means 10k and 10m respectively so that layer 13 can be detachably secured over portion 10e, and layer 13 is of a size to cover most of portion 10e. Portion 10a has secured thereto adjacent the waistline, by suitable stitching 10n, a strip or flap 16 which has a free lower edge. Strip 16 extends across substantially the whole width of portion 10a at the front inner side thereof.

In operation the portion 10a of the garment will be placed over the child's head and the arms will be extended through the sleeve portions 10c, portion 10d extending about the neck of the child. Portion 10e now hangs at the front of the child. The child will be provided with a diaper which will be put in place by fastening with safety pins to each end of flap 16. This will insure that the diaper or other underwear will be held up properly while the child is moving about or playing. Portion 10e is now brought between the legs of the child and folded upwardly substantially along its medium horizontal line and the fastening means or buttonholes 10j is buttoned onto the button 12 at the rear of the portion 10a. The corner parts of portion 10e are now

passed respectively around to the front of the garment and the fastening means or buttonholes 10i are buttoned to the button 11 at the front portion 10a. The garment now appears from the rear, as shown in Fig. 3, and from the front, as shown in Fig. 4. It will be seen that leg openings 10o are provided by the folded portion 10e. The garment is entirely protected by the layer 13 so that it never becomes wet or soiled. Should the child wet itself or have a natural passage, access to the diaper can be easily, quickly and conveniently had by merely unbuttoning the end of portion 10e and letting it hang, as shown in Figs. 1 and 2. The diaper can be unpinned from flap 16 and changed as usual. If the layer 13 is wet or soiled, it can be easily wiped off or cleaned. After the child has a fresh diaper placed thereon, portion 10e can again be folded up, passed around to the front and secured, as stated, and the child is again ready for play. The layer 13 can be easily and quickly detached and replaced if this is necessary or desirable.

In Figs. 6 to 9 a modified form of garment 20 is shown. This garment has a portion 20a extending above the waist, the front of which is continuous across the body or chest to the neck opening 20b. In the rear portion 20a extends only partially to the shoulders and has the shoulder straps 20c secured centrally thereto and extending upwardly in diverging relation. Straps 20c are secured at the other end to the front of portion 20a at the inner side thereof. Portion 20a is provided centrally at its front and around the neck portion with a gathered part or ruffles 20d. Said ruffles are joined together from the waistline to a point near the upper portion of the bodice and then separate and edge the bodice singly from said point to where the shoulder straps 20c are connected. A portion 20e extends downwardly from portion 20a at the front thereof and this may either be continuous with portion 20a or formed as a separate piece connected by a suitable seam 20f. Portion 20a has a pair of strings or pieces of tape 11 secured at one end thereto substantially centrally of the front of portion 20a adjacent the waistline. Portion 20a at its rear has a fastening means 12 secured thereto substantially centrally transversely thereof adjacent the waistline, and while said fastening means might take various forms, in the embodiment of the invention illustrated, it is shown as a button. The sides of portion 20e diverge downwardly so that said portion flares decidedly toward a lower free end, which end extends substantially horizontally. Said end will be provided with a suitable binding 20g. Portion 20e has, adjacent its free corners, fastening means 20h. Fastening means are also provided along its free end or along binding 20g intermediate the ends thereof, one of which 20i being disposed substantially centrally of binding 20g, as shown. While the form of fastening means 20i and 20h could be varied, they are shown as in the form of loops providing buttonholes. Portion 20e has on its inner or rear side adjacent its upper end spaced fastenings means 13. Portion 20e also has adjacent its lower end spaced fastening means 14. While the form of fastening means 13 and 14 could be varied, in the embodiment of the invention illustrated they are shown as tabs provided with buttonholes. A layer 15 of waterproof material is provided, having a shape similar to portion 20e and the same has fastening means 16 secured thereto adjacent its corners which are illustrated as

buttons. The fastening means 16 are adapted to be secured to the fastening means 13 and 14 respectively so that layer 15 will be detachably secured to portion 20e. As shown in Fig. 7, layer 15 is of a size to substantially cover the portion 20e. Portion 20e at its sides is provided with a gathered portion or ruffle 20j.

In operation the portion 20a will be placed over the child's head and the straps 20c will extend over the shoulders of the child. The arms are thus quite free. The child will be provided with a diaper or other suitable underwear and when the garment is placed in position, portion 20e will depend at the front of the child. Portion 20e is now brought rearwardly between the legs and folded upwardly substantially on a medium horizontal line. The loop 20i will be buttoned over button 12 at the rear and the corner parts of 20e will be passed around to the front of the garment respectively and strings 11 will be passed respectively through the loops 20h and then tied in a suitable manner as in the bow shown in Fig. 8. Layer 15 will of course have been placed in position. The diaper on the child or any other underwear can be fastened by safety pins at each end of flap 20f. The diaper of the child is covered by layer 15 so that the garment is protected from any wetting or soiling. Should it be necessary to change the diaper on the child, portion 20e can be very easily and quickly released to take its hanging position shown in Figs. 6 and 7. Layer 15 can easily be wiped off or cleaned if necessary, portion 20e again raised and secured in its operative position and the child is again ready for play or other activity.

From the above description it will be seen that I have provided a garment which is quite simple in construction, and which is pleasing in appearance. As described, the garment is protected by layer 13 from being wetted or soiled. The garment is also easily, quickly and conveniently manipulatable for changing the diaper or other underwear of the child. Another advantage of the garment is that it gives very great freedom of movement for the child. The child's arms and legs are largely exposed which is desirable in a summer garment.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. An outer garment for a child having in combination, a portion extending above the waist encircling the body and having arm and neck openings, said portion at the rear terminating substantially at the waist-line, said garment having a second and front portion extending from side to side of the same at the waist-line and extending downwardly to a line quite a distance below the crotch of the wearer, the side edges of said latter portion diverging to its bottom edge which edge extends substantially horizontally, said second portion being constructed and arranged to depend freely from its top, a fastening means disposed centrally at the rear of said first mentioned portion substantially at the waist-line, a second fastening means disposed centrally at the front of said first mentioned portion substantially at the waist-line, said second and front

portion being adapted to be passed rearwardly between the legs, then folded upwardly with said bottom edge disposed substantially at the waist-line and to have the corner portions thereof brought around to the front of said garment and to loosely overlie the upper central part of said second portion, fastening means at the ends of said lower edge of said second portion cooperating with said second fastening means at the front of said garment, and a fastening means at the central part of said lower edge of said second portion cooperating with said fastening means at the rear of said garment.

2. The structure set forth in claim 1, a belt extending along said lower edge of said second portion, the same having an elastic section intermediate its ends.

3. The structure set forth in claim 1, said second portion having laterally spaced fastening means adjacent its top and bottom and a sheet of waterproof material of trapezoidal form having a fastening means at its corners adapted to cooperate with said last mentioned fastening means.

4. An outer garment for a child having in combination, a bodice portion having parts extending over the shoulders and having arm and neck openings, said portion terminating at the rear substantially at the waist-line, said garment having a second and front portion extending from side to side of said garment and connected at its upper end to the front of said bodice portion, said second portion being of trapezoidal shape and having unbroken and substantially rectilinear side and bottom edges, said second portion being constructed and arranged to depend freely at the front of said garment, a fastening means disposed centrally of said first mentioned portion adjacent the waist-line and at the front thereof, a second fastening means disposed centrally of said first mentioned portion substantially at the waist-line at the rear thereof, fastening means adjacent the lower corners of said second portion and a fastening means adjacent the lower

edge of said second portion substantially centrally thereof, said second portion being adapted to be passed rearwardly between the legs of the wearer and its lower edge brought substantially to the waist-line, said last mentioned fastening means cooperating with said second fastening means, the lower corners of said second portion being adapted to be brought around to the front of said garment and freely overlie the upper part of said second portion, said fastening means at the corners thereof cooperating with said first mentioned fastening means.

JOAN M. BRENNAN.
